Specification of Letters Patent.

Patented Dec. 12, 1916.

Application filed June 8, 1912. Serial No. 702,432.

To all whom it may concern:

Be it known that we, HENRY L. SWEET, WALDO SWEET, and CHARLES B. T. HUTCHINS, citizens of the United States, residing at 5 Fond du Lac, in the county of Fond du Lac, at Fond du Lac, in the county of Fond du Lac, and at Menasha, in the county of Winnebago, in the State of Wisconsin, respectively, have invented certain new and useful 10 Improvements in Excavating-Machines, of which the following is a full, clear, concise, and exact description, reference being had to the accompanying drawings, forming a part of this specification.

15 Our invention relates to excavating machinery and contemplates certain improved features which go to make a simple, economical, and efficient machine.

Like other excavating machines, the device of our invention comprises a vehicle which carries a power plant and a shovel or scoop, the power plant being utilized to manipulate the scoop and for traction purposes.

25 Our invention is concerned with the manner in which the scoop is manipulated and with the provision of simple and effective mechanism for securing this manipulation. We contemplate also a particular form of 30 scoop and we provide an arrangement so that the forward end of the scoop faces the vehicle. The scoop is at the rear of the machine and is the last part to pass over the ground to be worked.

35 Machines of the kind to which our invention relates are used to a great extent for ditching and when the forward end of the scoop is made to face away from the machine, the vehicle must pass over the ditch, 40 spanning it like a bridge, and must ride upon the earth work on the sides as a bed. The arrangement is such that proper manipulation of the scoop is obtained, so that the vehicle may ride upon untouched 45 ground. Our machine can excavate double widths by throwing the earth on one side and then running along again and throwing it on the other side. In order that this may be so, it is necessary to accommodate numerous parts to this new theory of operation, and we have made these new arrangements the subject matter of the appended 50 claims.

The most difficult operations proposed for

excavating machinery are those of ditching 55 marsh lands, and it will be seen that the mode of operation of our device is particularly adapted to this use. Many features of our invention will be seen to be applicable to such a process. In view of this use of the machine, the traction wheels are made, 60 in the form of large drums so that a considerable bearing surface may be had and so that the weight may be as widely distributed as possible. The use of very wide rimmed traction wheels, like this, has been restricted, if not prohibited, by reason of the fact that the vehicle became too wide for running on country roads, in going about 65 from place to place, and this is so particularly in the case of bridges and the like which would not be made of such uncommon width. We provide a unique arrangement in the way of telescoping parts whereby the width of the drums may be changed 70 from broad to narrow when the vehicle is to go out upon the road and from narrow to broad when the vehicle is to be used in marsh lands or other lands where such a considerable bearing surface is desirable. 75

Our invention is embodied in the structure illustrated in the accompanying drawings, in which—

Figure 1 is a plan view thereof; Fig. 2 is a side elevational view thereof; Fig. 3 is an isolated detail sectional view showing the means for supporting the scoop pole; Fig. 4 is an isolated sectional view of the traction wheels and the directly associated parts; Fig. 5 is a detail view taken from the rear 85 of the machine and showing the turn table and the directly associated parts; and Fig. 6 is a plan view of the turn table and the directly associated parts. 90

Like reference characters are applied to 95 the same parts throughout the several views.

The main frame of the vehicle is illustrated at 7 and it will be seen from Figs. 1 and 2, that it is simply in the form of a rectangular platform which is required to carry the power plant and the various operating parts. As clearly shown in Fig. 4, this main frame 7, through the medium of suitable journal boxes 8, 8, is mounted upon tubular axles 9, which are prevented from shifting unduly to either side by means of collars 10, 10, held in place by means of set screws 11, 11. On each end of each tubular

axle, a wheel 12 is secured and it is evident that these wheels would be theoretically proper for traction purposes if it were not necessary to provide a greater tread surface than they, in themselves, provide. It will be seen that a supplementary axle 13 is inserted in each end of each tubular axle and has a considerable length of bearing therein. These supplementary axles fit tightly within the tubular axles and are held in any adjusted position by means of set screws 14, 14. Thus, we provide a telescoping arrangement, and at the free end of each of the supplementary axles 13 we provide a wheel 15 of substantially the same size as the wheels 12, 12. Instead of four wheels therefore, we have four pairs of wheels and the members of each pair may be disposed quite closely together or quite far apart as desired. Each pair of wheels is provided with a plurality of tread pieces 16, 16, which are connected across the two wheels and are held in place by means of removable bolts 17, 17. These tread pieces form the tread surface of the resulting traction drum and since they can be readily applied and taken off, it will be seen that the tread surface may be made large or small as desired. In fact, tread pieces of different length might be chosen from so that any desired width may be given to the traction drums. A very considerable width is desirable when the machine is working upon marsh lands and, as before pointed out, it is quite impossible to have such drums and at the same time have a practical machine which may be moved about from place to place, particularly along country roads. We thus propose the practice of using the wheels with the members of each pair drawn closely together, while the machine is upon the road, and of separating them and inserting the wide tread members when the machine has reached the land upon which it is to be used. In order to secure good traction under the working conditions of the machine, it is wise to make the tread strips alternately thick and thin, as clearly shown in Figs. 1 and 2.

Upon each of the tubular axles 9 we provide a sprocket wheel 18, and these sprockets are operatively connected by means of a sprocket chain 19. In connection with the front axle, the boxes 8, 8, instead of being secured directly to the frame 7, are secured to one member of a pair of steering plates 20, 20, the upper one being secured to the frame, and the lower one being that to which the axles are secured. Thus, the front axle 9 may oscillate for steering purposes and the chain and sprocket connection between the front axle and the rear axle is such as to admit of ample oscillation for practical purposes. The steering plates 20, 20 are in the form of annuli so that the corresponding sprocket wheel may be disposed inside them,

as illustrated in Fig. 1. Toward each end of the front axle a collar 21 is provided and this collar has a groove 22 in which a ring or hook 23 operates. Each hook is connected by means of a rope or cable 24 with a drum 25 mounted upon one end of the steering shaft 26, which, in turn, is set in bearings 27, 27 on the frame 7. Our invention is not concerned with the manner in which the shaft 26 is turned and it suffices to say that any means may be provided for turning it to admit of the proper steering of the machine.

In addition to the sprocket 18, the front axle 9 is provided with a sprocket 28 which, by means of a sprocket chain 29, is connected with another sprocket 30 mounted upon a shaft 31 suitably set in bearings in the frame. This shaft carries another sprocket 32 which, by means of a chain 33, is operatively connected with a sprocket 34 on the jack shaft 35 mounted in bearings 36, 36 on the frame 7. This jack shaft carries also another sprocket 37 which, by means of a chain 38, is operatively connected with sprocket 39 on the engine shaft 40 of a suitable engine 41. The sprocket 37 normally runs loose upon the jack shaft, but it may be operatively connected therewith by means of the clutch 37'. In this way, the engine speed is properly geared down to traction speed. The engine is shown quite diagrammatically in order to avoid unnecessary complication and to avoid illustration and description of arrangements with which our invention is not directly concerned. The engine may, of course, be connected to the rear axle, but the chain connection permits of the necessary oscillation of the front axle.

It is to be noted that we provide three drum shafts 42, 43, and 44, which are mounted stationarily and transversely of the frame in bearings 45, 46 and 47, respectively. The drum shaft 42 is provided with a drum 48 rotatably mounted thereon, the drum shaft 43 is provided with a drum 49 rotatably mounted thereon, and the drum shaft 44 is provided with the drums 50, 51 and 52 rotatably mounted thereon. It will be understood that these various drums are to be rotated in some suitable manner since our invention is not concerned with the particular way in which these drums are operated, and we have, for the sake of clearness, omitted any showing in this respect. These drums could be operatively connected with the engine 41 through the intervention of proper clutch mechanism, and such would be the most desirable arrangement. Suffice it to say that each of the drums can be turned upon its shaft for the purposes of drawing in or letting out the cables or ropes which are wound upon them, as will be described presently. At the rear of the machine, I provide the sturdy uprights 52', 52', which are braced from the front of the machine by 130

means of the bars 53, 53. A cross-piece 54 connects the tops of the uprights 52', 52', and a mechanically resistant superstructure is the result. Just below the cross-piece 54 there is provided another cross-piece 55, connected between the uprights 52', 52' and an oscillating block 56 is disposed between them (see Fig. 5). This oscillating block is mounted upon trunnions 57, 57, one in each of the cross-pieces, and upon each side of the block 56 there is secured, by means of a bolt 58, a rearwardly extending beam 59. Thus we have two pivoted, parallel beams which are cross-connected so as to secure a sturdy arrangement. In line below the trunnions 57, 57, a turn table 60 is coaxially mounted upon a pivot stud 61 set in a cross-piece of the frame 7, and this turn table has, extending rearwardly and upwardly therefrom two beams 62, 62 which are connected respectively with the ends of the rearwardly extending beams 59, 59, as illustrated in Fig. 2, the structure being reinforced by means of connecting bars 63. Thus, the beams 59 may swing about with the turn table, and this table in turn is provided with a sheave portion 64 which is adapted to receive a rope 65. One end of this rope is wound about the drum 50 and the other end is wound about the opposite drum 51 and as these drums are turned properly, the turn table is turned so as to swing the rearwardly extending beams from side to side.

At the rear end of each of the beams 59, a journal box 66 is secured and these journal boxes are arranged to house the trunnions 67, 67 extending from the sides of a collar 68 which is thus disposed between the two beams. This is a bearing collar which is shown in detail in Fig. 3 and which is adapted to receive the upright scoop pole 69 as clearly illustrated. The inner surface of the collar 68 is rounded as shown, and it will be noted that it constitutes quite a universal bearing for the pole 69, this pole having additional liberty of up and down movement parallel to its axis. At the top of the pole 69, a collar 70 is disposed and this collar is connected by means of a rope or cable 71 with the operating drum 49. The cable 71 passes under a guiding sheave 72 which is movably mounted at 73 upon a supporting plate 74 and is further guided between the sheaves 75 and 76, on the top of the cross-piece 54, and a roller 77 suitably supported from the cross-piece. It will appear that when the drum 49 is turned, the rope 71 will pull forwardly upon the top of the pole 69 and the pole will swing about the axis of the trunnions 67, 67. At the bottom of the pole 69 we provide a fork 78 to which the scoop 79 is pivoted at 80, 80. This scoop, as shown in the drawings, is made up of strips of metal passing lengthwise and crosswise and riveted together at the intersections. A collar 81 is adjustably secured upon the pole 69 and this collar by means of a brace rod 82 is connected with the rear end of the scoop. It will be apparent that as the collar 81 is adjustable up and down upon the rod 69, the rear end of the scoop may be raised or lowered so as to accommodate its position to the particular work in hand. The pole 69 is provided also with a collar 83 which has a rope or cable 84 secured thereto. This cable 84 passes upwardly and over a sheave 85 which has its trunnions 86 mounted in the beams 59, 59. The cable 84 then passes rearwardly and between the sheaves 75 and 76, over the roller 77, and down onto the drum 52. It will thus be apparent that when the drum 52 is turned in the proper direction, the pole 69 is raised and that when this drum is released, the pole and scoop will drop by gravity. Also mounted upon the pivots 80, 80 is a bail 86 to which a rope or cable 87 is secured. This cable 87 is guided between rollers 88 and over a roller 89, on the under side of the frame 7 and then passes upwardly and forwardly to the drum 48. It will appear that when the drum 48 is turned in the proper direction, the scoop 79 will be drawn toward the machine and consequently will be filled. In order that the machine may not be moved rearwardly while the scooping action is taking place upon the turning of the drum, we provide the rearward struts 90, 90, which are adapted to dig anchor-wise in the ground, as illustrated in Fig. 2, and which are rigidly mounted upon side extensions 91, 91, on the frame 7, as illustrated in Fig. 1.

The machine is adapted to move in the direction of the arrow *a* so that the scoop is at the rear of the machine and faces it. During the scooping action the scoop is drawn toward the machine and the scoop is then raised or moved to one side or the other to deposit the material excavated. In order that the scoop may have the proper lateral position, the drums 50 and 51 are manipulated to swing the turn table and the rearwardly extending beams 59, 59 to one side or the other. When this has been set, the drum 52 is released and the scoop 79 will drop down into place. If it is desired to have the scoop farther to the rearward, the drum 49 is operated and this brings the top of the pole 69 toward the front and the scoop will move back. If it is desired to have the scoop farther toward the front, the drum 48 is operated and this will draw it up. After the scoop has been set before the particular part which it is to pick up, the drum 48 is operated to draw in the rope 87 and this draws the scoop in to fill it. The next operation is to raise the scoop and this is done by setting the drum 52 into operation. This draws in the cable 84 and draws up the pole

69 so that it will move upwardly substantially parallel to its own axis through the collar 68. After the scoop has been raised sufficiently, the scoop being held in this position, the drum 49 is set into operation and the upper part of the pole 69 is drawn back so as to swing the scoop upwardly. This operation drops the earth from the scoop and the drums may then be worked so as to return the scoop to any desired position.

10 The form of scoop is important. Such a scoop encounters much less resistance than scoops heretofore used and is much lighter and more efficient. It has not the suction of other scoops to retain the material. As parts become worn they may be replaced without the provision of an entirely new device. The advantages of having the scoop in the particular position in which our 20 scoop is disposed, have already been pointed out, as have the advantages of the telescoping wheels. It is important that we use a "four-wheel drive" since we have found by experiment that such an arrangement is decidedly advantageous in practical use.

25 We claim as new and desire to secure by Letters Patent:

1. In an excavating machine, a frame, a 30 triangular beam extending from and pivoted to said frame, a pole sliding vertically in a swinging joint on said beam, said joint being disposed at the end of said beam, a cable attached to the top of said pole, a drum for said cable, a cable attached to said pole below said joint, a sheave for said second named cable disposed near said swinging joint, and a drum for said last named cable.

2. In an excavating machine, a frame, a 40 horizontally swinging triangular beam pivoted to said frame, a pole sliding vertically in a vertically swinging joint on said beam, a cable attached to the top of said pole, a drum for said cable, a lifting cable attached to said pole below said joint, a sheave for said lifting cable disposed near the swinging joint, and a drum for said last named cable.

3. In an excavating machine, a frame, a 45 beam extending from said frame, a pole sliding vertically in a swinging joint on said beam, an adjustable scoop carried by said pole, a cable attached to the top of said pole,

a drum for said cable, a cable attached to said pole below said joint, a drum for said second named cable, a guiding member for said second named cable disposed near said joint, a cable attached to said scoop, and a drum for said last named cable.

4. In an excavating machine, a frame, a beam extending from said frame, a pole sliding vertically in a swinging joint on said beam, an adjustable scoop carried by said pole, a cable attached to the top of said pole, a drum for said cable, a cable attached to said pole below said joint, a guiding member for said second named cable mounted close to 65 said joint, a drum for said second named cable, a cable attached to said scoop, and a drum for said last named cable, said scoop facing said frame.

5. In an excavating machine, a supporting 70 frame, a beam extending from said frame, a pole sliding vertically in a swinging joint on said beam, an adjustable scoop carried by said pole, a cable secured to the top of said pole, a drum for said cable, a cable fastened 75 to said pole near said scoop, a guiding member for said second named cable mounted in proximity to said joint, a drum for said second named cable, common guiding means for both of said cables disposed between said 80 drums and said pole, a cable attached to said scoop, and a drum for said last named cable, said scoop facing said supporting frame.

6. In an excavating machine, a supporting 85 frame, a beam extending from said frame, a pole sliding vertically in a swinging joint on said beam, a scoop carried by said pole, a cable attached to the top of said pole, a drum for said cable, a cable attached to said pole near the scoop, a guiding member for said 90 second named cable mounted in proximity to said joint, a drum for said second named cable, and common guiding means for both cables.

In witness whereof, we hereunto subscribe our names, this 4 day of June, 1912.
